E. ANDERSON

CHILD'S CRIB

Filed Sept. 18, 1925

INVENTOR:
Emil Anderson
BY David E. Carlsen
ATTORNEY.

UNITED STATES PATENT OFFICE.

EMIL ANDERSON, OF ST. PAUL, MINNESOTA.

CHILD'S CRIB.

Application filed September 18, 1925. Serial No. 57,198.

This invention relates to a collapsible crib for children and consists in the improvements hereinafter described and claimed, reference being had to the accompanying drawing, in which:

Fig. 1 is an end elevation of the improved crib.

Fig. 2 is a side elevation of the crib.

Fig. 3 is a side elevation of the crib in folded position.

Fig. 4 is an enlarged perspective view of one of the corners of the spring frame.

Fig. 5 is a top view, enlarged, of one of the corners of the crib about as at 5-5 in Fig. 1.

Fig. 6 is a plan view of the spring and its frame supporting the mattress.

Fig. 7 is a detail view of one of the metallic devices locking together the side and end sections of the crib when the latter is set up.

Referring to the drawing by reference numerals, 10, 10, designate the skeletonized end sections of the crib and having corner posts 11 normally upright and standing on the floor 12. The lower portion of each corner post is provided with a vertically disposed guide bar 13 on which is slidably mounted a hinge member 14 having an arm pivoted on a pintle 15 (see Figs. 4 and 5) comprising a part of a staple-like member 16 having three legs 17-18-19 secured in the corner of the spring frame 20 by nuts 21 or other means. Said frame 20 may be made of angle iron as in Fig. 6 or of wood as in Fig. 4, but in either case it is provided with depending legs 22 having casters 23 (shown in Figs. 2 and 3).

The staple like member forms also a second hinge pintle 24 (see Fig. 4) for a hinge member 25 secured as at 27 in Fig. 5, one near each end of each side section 26 of the crib and near the bottom edge thereof, while the upper corners of the side sections are each provided with means for securely latching it to the adjacent post of the end section, when the crib is set up for use.

Each of said corner latches is in the present drawing constructed as follows:

28-29-30 is a hasp of which 28 is the fixed part secured near the end of each top bar of the side walls or frames 26, 29 is the hinge and 30 the swingable plate or bar having two apertures 31-32 adapted to

straddle two staples 31* and 32* fixed one 55 in the side wall top bar and the other in the adjacent corner post 11 of the end section or on a projection 11a thereof. The hasp member 30 has two lugs 33 with a bolt 34 slideable therein and having a spring 35 tending at all times to push the bolt into locking position in the staples 31* and 32*.

The netting 36 in Fig. 6, which supports a mattress 37 in Figs. 2 and 3, I prefer to make of insulated copper wire so as to be 65 more durable in case it should be exposed to moisture. Its longitudinal edges are reinforced by double wires 38 slideable in the meshes of the netting. The netting 36 and wires 38 are suitably connected to the spring 70 frame by helical coil springs 39 in tension.

In the use or operation of the crib the spring frame 20 and its casters are suspended from the floor by the corner latches 30, and when the crib is not in use the bolts 75 34 are retracted, hasps 30 swung back as 30* in Fig. 5, the spring frame 20 and side sections 26 lowered until the casters 23 are on the floor, whereupon the side sections 26 are folded inwardly upon the mattress and the end sections 10-11 folded on top of the side sections as in Fig. 3. The entire structure, thus collapsed, is supported by the casters and may readily be rolled out of the way under a regular full size bed, 85 into a closet or other convenient place.

What I claim is:

1. A folding crib having end sections with corner posts forming supporting means when the crib is set up for use, vertically disposed guide bars fixed on the lower portions of said posts, a rectangular mattress frame with casters, hinge members fixed at each corner of said mattress frame, side sections of the crib pivotally engaging said hinge members of the mattress frame so as to be foldable upon the mattress, a latching device at each of the adjacent upper corners of the end and side sections to hold said sections together when they are in upright position, means on said end sections pivotally engaging the said hinge members of the mattress frame, said latter pivotal means being slideable on the vertical guide bars of the end sections.

2. The structure specified in claim 1 in which said hinge members at each corner of the mattress frame comprise a staple hav-

ing three legs secured in the frame and its top formed with two horizontal pintles at right angles to each other.

3. The structure specified in claim 1, in which each of the said corner latches consists of a staple or eye fixed near each other one on the end section and one on the side

section, a hasp hingedly secured to the side section and having apertures for said staples, two perforated lugs with a spring-actuated bolt slidable therein and arranged to enter said staples outside said apertures.

In testimony whereof I affix my signature.

EMIL ANDERSON.
